EXPANSION POST

Morton Waldman, 2550 Kemper Road, Cleveland, Ohio

Filed Apr. 23, 1962, Ser. No. 69,812

Term of patent 3½ years

(Cl. D13—4)

FIG. 2

The post in FIGURE 1 is broken away to indicate indeterminate length. The sides not shown are substantially the same in appearance as the sides shown in FIGURE 1.

I claim:

The ornamental design for an expansion post, substantially as shown and described.
